UNITED STATES PATENT OFFICE.

ARTHUR H. NOBLE, OF PAWTUCKET, RHODE ISLAND, ASSIGNOR TO THEODORE W. FOSTER & BROTHER COMPANY, OF PROVIDENCE, RHODE ISLAND.

DESIGN FOR A VANITY CASE.

Application filed November 23, 1927. Serial No. 24,246. Term of patent 14 years.

To all whom it may concern:

Be it known that I, ARTHUR H. NOBLE, a citizen of the United States, residing at Pawtucket, in the county of Providence and State of Rhode Island, have invented a new, original, and ornamental Design for a Vanity Case, of which the following is a specification, reference being had to the accompanying drawings, forming part thereof.

I claim:

The ornamental design for a vanity case, as shown.

In testimony whereof I have signed my name to this specification.

ARTHUR H. NOBLE.
